[57] ABSTRACT

A hermetic compressor unit comprising a hermetic casing containing a compressor including a cylindrical block having an arcuate surface engaging the inner surface of the casing and a suction tube assembly for connecting the compressor to a refrigeration system. The suction tube assembly comprises a tubular aluminum connector having a reduced end portion extending into a flanged hole in the casing and communicating with a suction passage in the block. A tubular fitting includes an end portion press fit into the passage and a shoulder portion press fit into the reduced end portion of the connector.

FIG. 4

HERMETICALLY SEALED COMPRESSOR ASSEMBLY

BACKGROUND OF THE INVENTION

In the manufacture of hermetic compressors for refrigeration systems, it is necessary to provide a fluid tight connector means for connecting the hermetic compressor unit to the refrigeration system.

Until recent years most of the conduits for connecting a hermetic compressor to a refrigeration system have been composed of copper or steel. When using such materials, the usual brazing techniques have been available for assuring a fluid tight joint between the copper or steel conduit and the steel compressor casing during final connection of the compressor to the system. Improved aluminum tubing has now become available for use in refrigeration systems and improved adhesives have made it possible to provide low cost tubular aluminum joints employing such adhesives. However, when an adhesive is used for these purposes, no brazing is available to seal the aluminum conduit component of the refrigeration system to the compressor casing in order to assure a fluid tight connector assembly.

SUMMARY OF THE INVENTION

The present invention is particularly directed to an improved hermetically sealed compressor unit assembly adapted to assure a fluid tight connection between an aluminum connector tube and the compressor casing whereby the aluminum connector can be adhesively joined to an aluminum conduit.

In accordance with the illustrated embodiment of the invention, there is provided a hermetic compressor unit comprising a steel casing including a cylindrical side wall and a compressor including a cylinder or compressor block having arcuate surfaces press fit or heat shrunk into contact with the casing side wall. The block includes a passage opening into an arcuate surface and the casing is provided with a flanged hole aligned with and larger than the passage. A tubular aluminum connector having a reduced end portion extends into the flanged hole to a point adjacent the arcuate surface of the block and zinc-aluminum soldered to the casing. A tubular steel fitting is driven into the connector and has an end portion press fit into the passage and a shoulder portion press fit into the reduced end portion of the connector thereby providing a direct connection to the passage and also a mechanical seal with the aluminum end portion of the tubing. The aluminum connector can thereafter be joined to an aluminum conduit forming part of a refrigeration system by an epoxy resin sealed joint.

BRIEF DESCRIPTION OF THE DRAWING

In the accompanying drawing:

FIG. 1 is a horizontal sectional view of a hermetic refrigerant compressor unit incorporating the present invention;

FIG. 2 is an enlarged sectional view taken along line 2-2 of FIG. 1 illustrating the construction of the connector portion of the unit;

FIG. 3 is a view similar to FIG. 2 illustrating one step in the manufacture of the compressor connector portion; and

FIG. 4 is a view similar to FIG. 3 illustrating the manner in which the connector tube is used for sealing the compressor for hermetic testing.

DESCRIPTION OF THE PREFERRED EMBODIMENT

With reference to FIG. 1 of the drawing, there is illustrated a hermetic rotary compressor unit comprising a cylindrical casing 1 in which there is disposed a rotary compressor 2. The compressor includes a cylinder block 3 having an inner cylindrical surface 4 which in combination with an end plate 5 and a second end plate (not shown) defines a compression cylinder 6 containing a rotor 7.

The cylinder block 2 includes diametrically opposed legs or extensions 8 having arcuate surfaces 9 engaging the inner surface of the cylindrical casing wall 1. In the manufacture of such a compressor, the cylinder block is either pressed into the casing or the casing is heat shrunk onto the cylinder block.

A suction passage 10 extends through the cylinder block from one of the arcuate surfaces 9 and into the compression cylinder 6. The outer end of this passage, as illustrated in FIG. 2 of the drawing, is in axial alignment with a flanged hole 11 in the casing side wall 1. A compressor of this general construction is shown in U.S. Pat. No. 3,568,712-Rinehart to which reference is made for a more detailed description of its construction and operation.

In accordance with the present invention, the hole 11 has a somewhat larger diameter than the passage 10 and the means for connecting the suction line of a refrigeration system to the passage 10 comprises a tubular aluminum connector 12 having a reduced end portion 14 extending into or through the hole 11 to a point adjacent the arcuate surface 9 of the compressor block. The reduced end portion 14 preferably has an outer diameter slightly smaller than the hole 11 to provide clearance for the brazing or soldering of the end portion 14 to the casing. This operation is preferably carried out using a zinc-aluminum alloy, the brazed joint being indicated at 19. A tubular fitting 15 is then employed to mechanically connect the connector 12 to the passage 10. This tubular fitting 15 inserted into connector 12 includes a reduced end portion 16 press fit into the passage 10 and a shoulder portion 17 press fit into the reduced end portion 14 of the connector and designed to firmly engage this end portion 14 of the aluminum connector in the area of the brazed joint 19 to form a fluid tight seal with the portion 14.

For assembly to the aluminum suction line 20 of a refrigeration system, the end of the line 20 is slip fit onto the connector 12 and adhesively bonded thereto by use of a suitable adhesive such as an epoxy cement.

In the manufacture of the compressor, the connector 12 is also employed for sealing the compressor during evacuation thereof prior to assembly into the refrigeration system. To this end, the connector, as shown in FIG. 3 of the drawing, is made longer than required for the system connection and is notched as indicated by numeral 22 for removal of the additional length. The fitting 15 is inserted through the open end of the connector 12 as shown in FIG. 3 and pressed into passage 10, the shoulder 17 expanding the connector portion 14 into mechanical engagement with the case opening 11. The connector is then brazed to the casing.

For evacuation of the compressor, the end of the connector 12 is pinched and sealed as shown in FIG. 4. After the testing, the sealed end portion is removed at the break-off notch 22 to provide a connector of the length shown in FIG. 2 which is then available for joining to the aluminum conduit 20. The press fit between the fitting 15, the reduced end portion 14 of the aluminum connector and the passage 10 in the cylinder block provides a hermetic seal so that no additional sealing is required to form a fluid tight connection between the compressor and the system. 10

While there has been shown and described a specific embodiment of the present invention, it is to be understood that it is not limited thereto and it is intended by the appended claims to cover all such modifications as fall within the true spirit and scope of the invention. 15

I Claim

1. A hermetic compressor unit comprising:
a casing including a cylindrical side wall;

a compressor including a cylinder block positioned in said casing and having an arcuate surface engaging the inner surface of said casing side wall; a passage in said block opening into said arcuate surface; said casing having a flanged hole aligned with and larger than said passage; a tubular aluminum connector having a reduced end portion extending into said flanged hole to a point adjacent said arcuate surface; and a tubular fitting having an end portion press fit in said passage and a shoulder portion press fit in said reduced end portion of said connector.

2. A compressor unit according to claim 1 in which 15 said aluminum tubular connector is zinc-aluminum soldered to said flange prior to insertion of said fitting.

3. A compressor unit according to claim 1 in which said tubular fitting is steel.
